UNITED STATES PATENT OFFICE

JOSEPH BENNETT HILL, OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA

OIL DISTILLING SYSTEM

Application filed May 14, 1926. Serial No. 109,005.

My invention relates to the art of distillation of hydrocarbon oils, such as petroleum and its products and oils derived from coal, shale and analogous materials.

5 In accordance with my invention, a body of the oil is heated by effecting combustion of a suitable fuel while submerged in and in direct contact with the oil, and more particularly, the aforesaid fuel comprises a mixture of a 10 combustible gas and a combustion-promoting gas, as air.

Further in accordance with my invention, a suitable gaseous mixture submerged in and directly contacting with a body of oil is ignited and the resultant gaseous products of combustion pass upwardly through and in direct contact with the oil for addition or transfer of heat thereto.

In the commonly used methods of distillation of hydrocarbon oils, the oil to be distilled is heated by indirect heat, conducted through the walls of the containing vessel which is usually built within or above a heating chamber. The walls of the vessel attain 25 a temperature considerably in excess of that of the oil due to the poor heat transfer from the metal container to and through the oil. As a result, the film of liquid immediately adjacent to the heated surface is subjected to 30 local overheating which, in the case of some oils, and particularly so with petroleum, may cause decomposition. This effect may be partially overcome by keeping the oil in motion either by passing it at high velocity through 35 heated tubes or by agitation, as by blowing steam through the liquid oil, but local overheating of the film is never completely eliminated by such means.

Furthermore, distillation by external application of heat to the container is relatively inefficient due to the heat loss in the flue gases, 40 radiation from the furnace, etc.

The external firing of stills, particularly those used for distilling petroleum, presents 45 further difficulty, in that when decomposition of the liquid occurs due to local overheating a layer of carbonaceous material or coke builds up on the still bottom and, due to its low thermal conductivity, the metal may become overheated resulting in damage to the still.

For the distillation of oils having boiling points which are in excess of the temperature at which substantial decomposition occurs it has been common practice to adopt some means to effect vaporization at a lower temperature. This may be done by distillation under vacuum or by passing through the liquid a heated gas or vapor, as steam, which by its partial pressure reduces the vapor pressure which must be exerted by the liquid in order that it may vaporize.

I have found that distillation of hydrocarbon oils may be economically effected by the use of a suitable burner, designed to burn a carefully controlled mixture of a combustible gas and an oxygen containing gas, such as air, immersed in a body of the liquid oil to be distilled and whereby combustion of the mixture may take place with the liquid oil as a surrounding medium.

70 In accordance with the method of this invention distillation of combustible liquids, particularly hydrocarbon oils, is effected by bringing the flames and products of combustion, resulting from burning of a suitable fuel, directly into contact with a body of the liquid (contained in a suitable closed vessel), thereby heating and vaporizing portions thereof. When using the immersed 75 burner as aforesaid I have found that combustion of the oil to be distilled can be avoided by carefully regulating the proportions of the gases in the gas mixture fed to the burner so that substantially no excess oxygen over that required for the gaseous combustion is present, and, therefore, the gases which enter the oil at flame temperature are 80 substantially free from oxygen and are unable to enter into combustion reactions with the oil.

By my process, I am able to avoid most of the difficulties mentioned above as attendant to the commonly used methods. Furthermore, as the products of combustion pass through the liquid they have the same effect of causing distillation at lower temperature than the application of steam or vacuum has in ordinary distillation.

85 My invention resides in the method and apparatus of the character hereinafter described and claimed.

For an understanding of my method and for an illustration of some of the various forms of apparatus within my invention reference is to be had to the accompanying drawings, in which:

5 Fig. 1 is a diagrammatic view of apparatus constructed in accordance with my invention.

10 Fig. 2 is an enlarged vertical sectional view showing a conduit supporting one form of ignition apparatus for igniting the gas traversing said conduit.

15 Fig. 3 is a plan view, partly in section, showing a plurality of ignition structures connected in an electric circuit.

20 Fig. 4 is a diagrammatic view of another form of apparatus constructed in accordance with my invention.

25 Fig. 5 is an enlarged vertical sectional view of a part of the structure shown in Fig. 4.

30 Referring to Fig. 1, there are illustrated the columns or supports 1 upon which rests a still A comprising the steel shell or jacket 2 enclosed by suitable heat or thermal insulating material 3. The oil to be distilled is charged to the level L through the line 4 controlled by the valve 5. The line 6 controlled by the valve 7 serves as a drawoff for the oil in the still.

35 A line 8 controlled by valve 9 leads from the dome 10 of still A to a condenser C mounted on suitable supporting structure 11. Connecting with condenser C is a line 12 leading to a gas separator S mounted upon the support 13. From separator S, oil may be passed to storage or other suitable destination through the line 14 controlled by valve 15. Communicating with the top of the gas separator S is a line 16 controlled by a valve 17 through which the uncondensed gases may be passed to an oil recovery system, not shown.

40 In accordance with my invention the oil contained in still A is heated by effecting combustion of fuel while submerged in and in direct contact with the oil. To this end, when a gaseous fuel mixture is utilized, a pipe or conduit 18 mounted interiorly of and adjacent the bottom of still A may project exteriorly thereof into communication with a mixing chamber 19 into which opens a pipe or conduit 20 controlled by a valve 21, a suitable pump 22, or equivalent, being utilized to force air or other combustion-gas promoting gas, hereinafter generically termed "air," along conduit 20 into chamber 19. A second pipe or conduit 23 controlled by a valve 24 has interposed therein a pump 22a or the like utilizable for forcing a combustible gas, preferably one produced in petroleum distillation, along conduit 23 into the chamber 19.

45 Conduit 18, interiorly of still A, is provided with a plurality of lateral openings

50 preferably threaded to receive the exteriorly threaded end portions of the cylinders or tubes 25, preferably metallic in character, Figs. 2 and 3. Each tube 25 adjacent its other end is provided with a plurality of perforations 26, preferably circumferentially arranged, and forming the sole means of communication between the interior of conduit 18 and the interior of the still A. Mounted in each tube 25 is a plug or diaphragm 27, 55 preferably of metal. When an electrical arrangement is utilized for igniting the gas passing into the body of oil in still A, it is desirable, when tubes 25 and plugs 27 are constructed of metal, that a member 28 of suitable insulating material be disposed between each plug 27 and the adjacent surface of the tube 25 associated therewith. Each plug 25 is provided with one or more passages or orifices 25a of restricted diameter.

55 The combustible mixture issuing through passages 25a may be ignited in any suitable manner. Merely by way of example, I have illustrated one type of ignition apparatus for producing electric sparks adjacent the outlets of passages 25a. To this end, each plug 27 may be provided with a spark gap structure comprising a pair of discharge points 29 and 30, the former being welded or otherwise suitably secured in conductive relation to plug 27 and the latter extending through a passage therein but insulated therefrom by a member 31 of suitable insulating material, as mica. As well understood in the ignition art, the tips of discharge points 29 and 30 should be spaced a suitable distance apart to insure the development of sparks of the proper characteristics.

60 As herein shown by way of example, conductors 32 and 33 pass from a suitable source of high tension current, as the induction coil 34, interiorly of conduit 18 for connecting the pairs of discharge points 29 and 30 in series. Low tension current is supplied from any suitable source to coil 34 by conductors 35 and 36 in one of which may be interposed the switch 37.

65 With the oil charged in the still to the level L, the air and gas pumps 22 and 22a are placed in operation and, by adjustment of valves 21 and 24, the desired proportions of gas and air are passed to the mixing chamber 19, where thorough mixing occurs, and thence to the conduit 18. From conduit 18, the combustible mixture passes through passages 25a in plugs 27 of the submerged burners at a velocity sufficiently high to prevent back-firing into conduit 18 when the issuing mixture is ignited in the tubes 25 beyond the plugs 27. The velocity of the issuing combustible mixture is also sufficiently high to prevent flow of the oil from still A through passages 25a to the interior of conduit 18. Upon closure of contact key 37 a spark is passed between each

pair of discharge points 29 and 30, thereby igniting the combustible mixture. The flame issues from the perforations 26 in direct contact with the oil, thereby imparting heat and raising the oil temperature. The gaseous products of combustion pass upwardly through the oil and cause further heating.

In the early stage of distillation very little oil vapor passes with the products of combustion from the still A to the condenser C through the line 8 due to the low vapor pressure of the oil at low temperatures. As the temperature rises the quantity of the oil vapors in the exit gases from the still increases with the vapor pressure of the oil. Distillation finally takes place at such a temperature that the vapor pressure of the oil will give a ratio of oil vapors to combustion gases such that there is effected heat balance between the heat of combustion of the burner gases and the latent heat of vaporization of the oil. Under these conditions the oil is distilled at a temperature considerably below its boiling point producing the same effect as distillation with steam in the commonly practiced methods.

The temperature of still A may be regulated by dilution of the combustible mixture with an inert gas obtained from any suitable source of supply. By preference, however, such inert gas is obtained by recycling a desired portion of the spent combustion gases after the oil vapors have been condensed therefrom. To this end and as herein shown, the line 16 through which the gases pass from the gas separator S may be tapped by the line 38 controlled by the valves 39 and 40 for passing a desired quantity of spent gases to the inlet conduit 41 of pump 22a, such spent gases eventually reaching the chamber 19 where mixing occurs with air and the combustible gases.

The temperature of still A may also be regulated by operation of valve 9 to vary the pressure thereon. An increase in pressure has the effect of increasing the partial pressure of the combustion gases. Since the ratio of the weights of oil distilled to combustion gases and, therefore, the ratio of the partial pressure of the oil vapor to that of the gases is fixed by the heat balance and is approximately independent of pressure, the partial pressure of the oil vapor, that is the vapor pressure of the liquid oil, must be correspondingly increased. Equilibrium will, therefore, be reached at a higher temperature due to the increased pressure of the system. Similarly a decrease in the pressure of the system will result in a lower still temperature.

Since in my process the heating of the oil is done directly by the flame and the hot gases, the presence of a more or less permanent film at the heating surface is eliminated and thermal decomposition of the oil in the film thereby avoided. The distilling liquid is main-

tained by the gases in a state of vigorous agitation and there is little possibility of superheated zones. The process has the additional advantage of very high thermal efficiency, since the radiation losses are low due to complete heat insulation of the still, and since the issuing combustion gases are only at the temperature of the still. Furthermore there is no contact between the flame or hot gases and the metal of the still and therefore no possibility of damage to the still due to overheating.

While my invention has been described above in connection with a shell still, it shall be understood that such description is definitive rather than limitive. As another aspect of my invention, I have illustrated in Figs. 4 and 5 a pipe still A1 comprising the tubes, pipes or conduits 50 embedded in suitable heat insulating material 51. As shown, the ends of tubes 50 extend beyond the material 51 and are connected in series by the U-shaped coupling tubes or return bends 52 secured to the ends of adjacent tubes in any suitable manner; for example, by securing flanges 53 forming the terminals of U-tubes 52 to corresponding flanges 54 forming the terminal of pipes 50 by bolts 55 or the like.

Connected to the lowermost pipe 50, as viewed in Fig. 4, is the line 56 leading to a suitable separating device herein shown as the fractionating column F1 comprising the spaced plates 57 provided with the bubbler cap structure 58 and down flow pipes 59. Communicating with the bottom of column F1 is the line 60 leading to storage or other suitable destination. If desired, portions of the reflux liquid descending through column F1 may be withdrawn at different levels, by the trapped lines 61 and 62 controlled, respectively, by the valves 63 and 64, through the coolers 65 and 66 and thence to storage.

A line 67 leads from the top of column F1 to a condenser C1 from which a line 68 leads to a gas separator S1. Communicating with the bottom of separator S1 is a line 69 opening into a flow box B1 to which is connected a line 70 for passing a stream of liquid oil to storage. If desired, there may be provided a conduit 71 for passing oil from flow box B1 to column F1 where it serves as refluxing liquid.

A combustible mixture of a gaseous fuel and air may be passed into direct contact with the oil flowing through the tubes 50 in any suitable manner. By way of example, I have shown the U-shaped coupling tubes 52 at each end of the still provided with bosses 72, each interiorly threaded to receive the exteriorly threaded end portion of a tube or cylinder 73 corresponding generally with the tubes 25, Fig. 1. The ends of cylinders 73 in which are formed the perforations 26 extend well within the tubular structure comprising the pipes 50 and U-shaped coupling tubes 52 while the

other ends of said cylinders 73 extend exteriorly of the coupling tubes 52 and, by suitable fittings 74, 75 and 76 are connected to the conduit system 77 through which passes the combustible mixture from any suitable source, not shown, as a mixing chamber and associated pumps for supplying a similar mixture to and through the conduit 18, Fig. 1.

In the example illustrated, cylinders 73 are equipped with spark gap structures of the character shown in Figs. 1, 2 and 3, the coacting electrodes or sparking elements 29 and 30 of all the structures being connected in series by the conductors 32 and 33 leading from the induction coil 34 into the conduit system 77 through which they are extended to the various spark gap structures.

The operation of the form of my invention shown in Figs. 4 and 5 is essentially the same as described above with respect to Figs. 1, 2 and 3. Oil is pumped to the still through the extension 50a of the uppermost tube and thereafter flows through the tube structure in the direction indicated by the arrows, Fig. 4. At the same time, the combustible mixture is supplied through the conduit system 77 and, after the air has been expelled from the tube structure 50, 52 by the oil, switch 37 is closed to ignite the combustible mixture, the products of combustion thereafter thoroughly mixing with the oil.

The heated mixture of oil, vapors and combustion products pass from still A1 through the line 56 to the fractionating column F1 in which the gases and vapors pass upwardly in contacting relation with the descending reflux liquid, the unvaporized oil being drawn from the bottom of the column through line 60. The vapors pass from the top of column through line 67 to condenser C1 and thereafter through line 68 to separator S1. If desirable, and in a manner similar to that described above with respect to Figs. 1, 2 and 3, gases for dilution purposes may be transferred from the separator S1 by way of line 78 controlled by valve 79 to the intake of the pump supplying a combustible gas to the conduit system 77.

It will be observed that the cylinders 73 and associated spark gap structure are so located in the tube structure 50, 52 that the burning gases issue from the perforations 26 in the direction of flow of the oil thus aiding in its passage through the tubes. Should the oil be pumped into still A1 through the lowermost tube of the series, cylinders 73 and associated structure would preferably be located in the upper portion of the U-shaped tubes 52 so that the burning gases would still issue in the direction of flow of the oil.

What I claim is:

1. A process for distilling hydrocarbon oil, which comprises mixing in a zone combustible, oxygen-containing and inert gases, pass-

ing the gaseous mixture from said zone into a body of oil, burning the gaseous mixture while submerged in and in direct contact with the oil, collecting the products of combustion, and introducing at least a portion 70 of said products into the zone wherein are mixed the combustible, oxygen-containing and inert gases.

2. In combination with a still for vaporizing hydrocarbon oil, means within the still 75 for heating the oil comprising a conduit extending adjacent the bottom of said still, means for conducting a combustible gas into said conduit, burners communicating with said conduit, and means within said burners 80 for igniting the combustible gas, whereby flames resulting from combustion of said gas are submerged in and directly contact with the oil.

3. In combination with a still for vaporizing hydrocarbon oil, means within the still for heating the oil comprising a conduit extending adjacent the bottom of said still, means for mixing a plurality of gases, means for introducing the gaseous mixture into said 90 conduit, burners communicating with said conduit, and means within said burners for igniting the gaseous mixture.

4. In combination with a still for vaporizing hydrocarbon oil, means within the still 95 for heating the oil comprising a conduit extending adjacent the bottom of said still, a mixing chamber, means for separately supplying gases to said chamber, means connecting said mixing chamber and said conduit, burners communicating with said conduit, and igniting means within said burners.

5. In combination, a still for heating hydrocarbon oils, a conduit within the still adjacent the bottom thereof, means for conducting a combustible gas into said conduit, burners communicating with said conduit, and igniting means associated with said burners, whereby flames resulting from combustion of said gas are submerged in and 100 directly contact with the oil.

6. In the art of distilling hydrocarbon oil, the method which comprises burning a combustible mixture while submerged in the oil, effecting direct contact of the products of combustion with the oil, and controlling the temperature resulting from the combustion by regulating the pressure upon the body of oil.

7. In the art of distilling hydrocarbon oil, 120 the method which comprises burning a combustible mixture while submerged in the oil, effecting direct contact of the products of combustion with the oil, and controlling the temperature resulting from the combustion by diluting the combustible mixture with an inert gas prior to its introduction into the oil.

JOSEPH BENNETT HILL.
